DESIGN FOR A NAIL FILE

Maximilian Schnefel, East Orange, N. J., assignor to Schnefel Brothers, Inc., Newark, N. J.

Application May 22, 1935, Serial No. 56,957

Term of patent 7 years

To all whom it may concern:

Be it known that I, Maximilian Schnefel, a citizen of the United States, residing at East Orange, in the county of Essex and State of New Jersey, have invented a new, original, and ornamental Design for a Nail File, of which the following is a specification, reference being had to the accompanying drawing, forming a part thereof.

The drawing represents a plan view of a nail file embodying my new design. The portion shown in light lines is merely conventional.

The design of the nail file is substantially the same on both sides as shown on the drawing.

I claim:

The ornamental design for a nail file as shown and described.

MAXIMILIAN SCHNEFEL.
